UNITED STATES PATENT OFFICE

SERN MADSEN, OF CLINTON, IOWA, ASSIGNOR TO CURTIS COMPANIES, INCORPORATED, OF CLINTON, IOWA, A CORPORATION OF IOWA

WEATHERPROOF WINDOW CONSTRUCTION

Application filed June 10, 1931. Serial No. 543,305.

The object of my invention is to provide a very simple and efficient construction for providing weatherproof windows.

More particularly, it is my object to provide a weatherproof construction including a grooved jamb, a peculiarly grooved sash and what may be called a resilient double leaf double contact weatherstrip.

Another purpose is to provide such a construction that will allow for some lateral shrinkage or movement of the sash relative to the window frame and also allow some in-and-out movement of the sash between the stops without interfering with the maintenance of weatherproof joints and without allowing rattling.

Still another purpose of the present invention is to provide a weatherproof construction of the kind mentioned by which there may be obtained a predetermined amount of frictional resistance to the sliding movement of the sash to accommodate and compensate for slight variations in the sash balance whether of the spring or weight and cord type.

With these and other objects in view, my invention consists in the construction, arrangement and combination of the various parts of my weatherproof window construction, whereby the objects contemplated are attained, as hereinafter more fully set forth, pointed out in my claims, and illustrated in the accompanying drawing, in which:

Figure 1 is a perspective view partly in section with parts broken away of a part of a side jamb and one corner of a window sash equipped with a weatherstrip, the whole structure illustrating my invention.

Figure 2 is a horizontal, detail, sectional view illustrating the window frame and sash, the weatherstrip structure and a spring sash balance arrangement.

Figure 3 is a sectional, perspective view of a section of weatherstrip partly broken away.

Figure 4 is a small, horizontal sectional view showing a portion of a sash and a portion of the side jamb of a slightly modified form of the invention.

Figure 5 is a vertical sectional view of

a portion of the sash and sill illustrating the manner in which the free floating mounting of the sash facilitates registration between the sash and the sill weatherstrip.

In the accompanying drawing, I have used 55 the reference numeral 10 to indicate the side jamb of a window frame having the side casings 11 and 12, the blind stop 13, the parting stop 14 and the inside stop 15. At 16 and 17, I have indicated generally the lower and 60 upper sash of an ordinary double hung sliding sash window.

My improved construction may be used with windows of the kind hung with weights and ropes and pulleys, but I prefer to use it 65 with sash that are spring supported.

I have therefore illustrated the window structure in the drawing with the supporting coil springs 18.

It will, of course, be understood that the 70 springs 18 are secured at their lower ends to the window sash and at their upper ends to the jamb 10. They may be secured at various heights on the jamb and may be fastened detachably or otherwise in any suitable way 75 at their lower ends to the sash.

Where springs are used for sash balance purposes, it is important to control the movement of the sash.

I have provided means whereby this 80 resistance or movement of the sash can be secured and maintained while permitting a rather free floating movement of the sash between the stops and providing for limited lateral play between the sash and side jambs. 85 All of this I have obtained by my construction while maintaining a weathertight joint.

For providing these advantages, the side jambs 10 are provided with opposite grooves 19. Each side jamb has in its face adjacent 90 to the window sash one such groove for each sash extending the full length of that portion of the side jamb engaged by the sash, to-wit, from head jamb to sill. This groove 19 may be provided with a channel-shaped metal 95 lining 20, as shown for instance in Figure 1, or the lining may be omitted as shown in Figures 2 and 4 under some circumstances. The lining must terminate at least flush with the face of the jamb.

Each sash stile 21 and the adjacent ends of the top rail and base rail of each sash are provided with a groove 22 extending lengthwise the full length of the sash and arranged 5 to travel opposite a corresponding groove 19.

In the mouth of the groove 22 is a wide groove 23. (Figure 1.) A weather strip, indicated generally at A, (Fig. 3) has an anchoring portion 24 designed to be inserted 10 into the groove 22, as shown for instance in Figures 1, 2 and 4.

I preferably make the weatherstrip of a single piece of somewhat resilient sheet metal, but it is obvious that it could be made of more 15 than one piece.

When made of one piece, the metal is folded along a middle vertical line and the anchor portion 24 is formed of two layers folded one over against the other, as shown best in 20 Figure 3.

The metal is then bent in opposite directions away from the anchor portion 24 to form a channel-like portion having a base formed of the parts 25 extending away from 25 the anchor portion 24, and the sides 26.

Preferably the sides 26 are inclined from the base 25 somewhat toward each other for about half the width of the sides and are then inclined away from each other as indicated respectively at 26a and 26b. I am 30 referring now to the normal shape of the weatherstrip.

The outer edges of the sides 26 may be rolled as at 27.

35 In Figures 2 and 4, I have shown a slightly different form.

The parts are preferably so arranged that the sides 26 snugly fit between the faces of the groove 23 adjacent to the base members 40 25 and the portions 26b of the sides 26 project from the groove 23. Thus the portions of the sides 26 which are spread farthest from each other engage the walls of the channel lining 20 or the opposite walls of the groove 45 19, as the case may be.

The structure being a factory product, the tension of the two sides 26, which for convenience I call the resilient leaves of the weather strip can be accurately determined 50 and regulated. Thus they can be given such tension when shoved into the groove 19 as may be desired.

On account of the peculiar construction of the sides 26, it will be seen that the sash can 55 be hung to float as it were between the stops. The sash can have a little in-and-out play between the stops. This play is limited by the weather strip, but a little of it is permitted by reason of the inclination of the parts 26a 60 toward each other and of the parts 26b of each weatherstrip away from each other.

In Figure 4, I have illustrated how this play may occur and have shown the sash 16 moved a little away from where the grooves 65 23 and 19 truly register. Such play, it is

seen, may be permitted to some extent without interfering with the weathertight joint and without destroying the frictional resistance between the weatherstrip and the window jamb.

70 On account of the fact that it is extremely difficult to hang the window sash with exact accuracy, the provision of a little such play is desirable. For instance, where sash are spring hung as illustrated, it becomes quite 75 important to not have any binding other than that provided for by the resiliency of the weatherstrip.

If windows are installed snugly between the stops, then it is obvious in wet weather, 80 windows are likely to bind. It is therefore desirable to install sash with a slight looseness between the stops. Unless some provision were made to take care of noise, it is obvious that a loose installation of the sash would 85 be undesirable.

In the present case, the weatherstrip prevents any such noise or rattling.

It will be observed that a little lateral play 90 of the sash may be permitted where these weatherstrips are used without interfering with the tight joint and without any danger of rattling.

The sides 26 can slide in the grooves 19. This allows a loose enough installation of the 95 sash to prevent binding in wet weather.

It is, of course, obvious that with the structure explained, if the window installation is originally tight and the parts of the window dry out and shrink, weathertight joints will 100 still be maintained by the weatherstrip and the shrunken sash will be prevented from rattling.

Another and quite important feature of the present invention lies in the fact that there 105 are two distinct contacts or lines of weather-tight joint.

Each of the side members 26b engage a wall of the groove 19 or of its lining and thus there is a double engagement of the resilient 110 leaves or sides of the weatherstrip for preventing passage of air around the sash.

The anchor portion 24 may be so made as to cause it to resiliently grip the walls of the groove 22. The weatherstrip can thus be held 115 in place temporarily during installation.

To insure positive fastening of the weatherstrip, the anchor portion 24 is provided with holes 28 to receive screws 29 inserted in the 120 stiles or rails of the sash.

To prevent up-and-down leakage of air, the sides 26 are extended a little above and below the anchor portion 24, and are bent to overlapping position as indicated at 30 and 31 for closing the upper and lower ends of 125 the weatherstrip.

The advantages of such a structure are largely seen from the foregoing explanation.

There is another advantage in the possibility of mounting the sash for a little in-and- 130

out floating movement. If the window is provided at the top and bottom with the ordinary rib and groove weatherstrips, it is obvious that they vary slightly, and if the effect of 5 their proper coaction is to swing the sash just a little inwardly or outwardly, such movement of the sash is freely permitted without interfering with the weatherstrip arrangement.

10 In Figure 5, I have shown the sill 32 provided with a ribbed weatherstrip 33 and the sash 17 provided with a groove 34 for illustrating the construction just explained.

Another advantage of the construction 15 here shown arises from the fact that the pressure of the resilient leaves of the weatherstrip is perpendicular to the plane in which the sash travels. This pressure will remain the same regardless of any expansion or 20 shrinking of the sash and where a metal liner is used for the jamb groove, regardless of any shrinking or expansion of the jamb.

The sash is loosely mounted in the frame 25 in such manner as to avoid any substantial friction between sash and frame. The weatherstrip thus serves to hold the sash in its proper position against in and out movement and against sidewise and practically 30 the only friction involved in sliding the sash is that between the weatherstrip and the jamb. This is what I call "free floating movement".

With such an arrangement, it is possible 35 to provide a spring for balancing the sash and to accurately control the friction between sash and frame. This solves one of the big problems in building windows.

With wood frame and wood sash construction, it is difficult to use springs for balancing the sash because the swell and shrink 40 of the material sometimes causes the parts to unduly bind and sometimes results in too little friction and sometimes permits them to 45 rattle and allows too much flow of air around the sash. With my construction all of these difficulties are eliminated.

I design the spring to actually balance the 50 sash in its position at the middle of its sliding movement. The spring is designed to give minimum variation in decrease or increase of tension as the sash moves up or down. The amount of unavoidable under 55 balance or overbalance of the sash with relation to the spring as the sash moves up or down from its midway position is compensated for by means of friction imposed between the sash and frame. By the structure 60 herein provided, this friction may be made definite and constant and may be accurately predetermined.

I provide a weatherstrip calibrated to have 65 a uniform friction per unit of length. This always slightly exceeds the amount of un-

balance, so as to prevent creeping of the sash up or down.

The weatherstrip resiliently furnishes a "damping" force, resisting movement of the sash, never imposing any recall or return 70 force as between sash and frame.

It is noted that the friction always remains the same because the weatherstrip unit is carried by the sash and is of the same length as the sash. Such a result could not be obtained if the weatherstrip projected from the jamb into the sash and did not extend the full length of the window, as is sometimes the case.

The same springs can be used for sash of 80 different length because such sash have longer weatherstrip units and thus there will be afforded greater friction when the spring is extended to greater length.

The weatherstrip not only affords accurately controlled friction between sash and frame necessary when springs are used for counterbalancing the sash, but also affords proper weathersealed joints. These are especially necessary where there is no binding 85 between the sash and the frame.

It will be noted that such a type of weatherstrip with the constant accurate determination of friction between sash and jamb has an advantage if used with the ordinary 95 weight and pulley sash balance.

Heretofore there have been made weatherstrip installations in which grooves have been used for the insertion of weatherstrip elements. Likewise resilient leaf devices 100 have been used, but so far as I am aware none have been used which are like the present device in structure.

Furthermore so far as I am aware, none of the previous devices have been constructed so that the coaction of the resilient weatherstrip element with either the frame or the sash constituted practically the only means of frictional contact so as to make possible the accurate control and maintenance of a 110 predetermined amount of friction.

In all previous devices of which I have any knowledge, there was some friction of wood or metal on wood and that friction would vary depending upon the swell and shrink 115 of the wood.

It is, of course, obvious that some changes might be made in the details of the construction and arrangement of the parts of my invention without departing from the principal features and purposes thereof, and I desire to cover by the patent to be issued upon my application any modifications in structure or use of mechanical equivalents which may be properly included within the scope 120 of my invention and of my claims.

I claim as my invention:

1. In a weatherproof window structure, a window sash having grooves in its stiles with 130 wider portions at their outer parts, the win-

- dow frame having side jambs provided with grooves, weather strips with anchoring portions received in the inner parts of the grooves in the stiles and with spaced resilient leaves
- 5 in the wider portions of the grooves in the stiles and projecting therefrom into the grooves in the jambs and bearing resiliently against the walls of said latter grooves.
2. In a weatherproof window structure, a
- 10 window sash having grooves in its stiles with wider portions at their outer parts, the window frame having side jambs provided with grooves, weather strips with anchoring portions received in the inner parts of the grooves
- 15 in the stiles and with spaced resilient leaves in the wider portions of the grooves in the stiles and projecting therefrom into the grooves in the jambs and bearing resiliently against the walls of said latter grooves, said
- 20 jamb grooves being provided with metal lining for engaging the leaves.
3. In a weatherproof window structure, a window sash having grooves in its stiles with wider portions at their outer parts, the window frame having side jambs provided with grooves, weather strips with anchoring portions received in the inner parts of the grooves in the stiles and with spaced resilient leaves
- 25 in the wider portions of the grooves in the stiles and projecting therefrom into the grooves in the jambs and bearing resiliently against the walls of said latter grooves, said leaves being spaced from the walls of the
- 30 wider portions of the grooves in the stiles, except adjacent to the narrow grooves in the stiles to permit some lateral movement of the sash with relation to the jamb.
4. In a weatherproof window construction,
- 35 the combination of a frame having side jambs provided with vertical grooves and a sash having stiles provided with vertical grooves in their faces, and having narrower grooves at the bottoms of the first grooves, with
- 40 weatherstrips each having an anchoring portion received in the inner grooves of a stile and channel-shaped portions projecting from the anchoring portion and provided with side walls inclined from the bases of such channel
- 45 portions slightly toward each other and thence away from each other, the latter inclined portions being projected from the grooves in the stiles and into the grooves in the jambs for forming resilient leaves en-
- 50 gaging the opposite walls of the jamb grooves.
5. A weatherstrip formed of a single strip of sheet metal folded along a median line to form a double thickness anchor section, the metal then being bent in opposite directions
- 55 away from said section to form the base of a channel and thence away from said base to form channel walls, the walls being slightly inclined toward each other for a portion of the width thereof and thence slightly away
- 60 from each other.
6. A weatherstrip formed of a single strip of sheet metal folded along a median line to form a double thickness anchor section, the metal then being bent in opposite directions away from said section to form the base of a channel and thence away from said base to form channel walls, the walls being slightly inclined toward each other for a portion of the width thereof and thence slightly away
- 65 from each other, and being formed with convex surfaces near their outer edges.
7. A weatherstrip for sealing the joints between two window members formed of resilient sheet metal folded lengthwise to form a rib-like anchoring portion and then folded to form right-angled offset portions, comprising the base of a channel, and then folded to form channel walls comprising two resilient leaves extending from the offsets and having converging and then diverging slopes.
8. A weatherstrip for sealing the joints between two window members formed of resilient sheet metal folded lengthwise to form a rib-like anchoring portion and then folded to form right-angled offset portions, comprising the base of a channel, and then folded to form channel walls comprising two resilient leaves extending from the offsets and having converging and then diverging slopes,
- 90 and having at their outer parts outside convex surfaces designed for sliding contact with one window member when the rib portion is attached to another coacting window member.
9. A weatherstrip for use between two window members formed of resilient metal folded lengthwise to form an anchor portion for attachment to one window member and then folded to form spaced leaves substantially parallel with each other having resilient sliding contact with appropriate faces of a second window member.
10. In a window construction, a frame element, a sash element vertically slidable therein, spring means tending to balance the sash at an intermediate point in its vertical movement, said elements having at each side coacting guide and engaging means comprising spaced substantially parallel vertical faces and spaced members for yieldingly engaging said faces for frictionally resisting vertical sliding movement of the sash and permitting limited movement of the sash between the sides of the frame and allowing in and out movement of the sash, said members being in engagement with said faces for the full height of the sash during the full travel thereof whereby the sash will be held in any position of vertical adjustment when not balanced by the spring means.
11. In a window structure, a frame having stops, and vertical grooves, a vertically slideable sash mounted for limited movement between the sides of the frame and in and out
- 95

movement between the stops, spring means to yieldingly substantially balance the sash at an intermediate point in its vertical movement, devices carried by the sash each having 5 spaced leaves co-extensive with the height of the sash and bearing resiliently against the side walls of a groove for providing uniform friction to hold the sash in any position of vertical adjustment when not balanced by the 10 spring means and to permit horizontal lateral and in and out floating of the sash and for serving as a weather seal.

12. In a window construction, a frame element, a sash element vertically slidable therein, said elements having at each side coacting 15 guide and engaging means comprising spaced substantially parallel vertical faces and spaced members for yieldingly engaging said faces for frictionally resisting vertical 20 sliding movement of the sash and permitting limited movement of the sash between the sides of the frame and allowing in and out movement of the sash, said members being in engagement with said faces for the full 25 height of the sash during the full travel thereof whereby the sash will be held in any position of vertical adjustment.

13. In a window construction, a frame element, a sash element vertically slidable therein, spring means tending to balance the sash 30 at an intermediate point in its vertical movement, said elements having at each side coacting guide and engaging means comprising spaced substantially parallel vertical faces 35 and spaced members for yieldingly engaging said faces for frictionally resisting vertical sliding movement of the sash and permitting limited movement of the sash between the sides of the frame, whereby the sash will be 40 held in any position of vertical adjustment when not balanced by the spring means.

14. In a window construction, a frame element, a sash element vertically slidable therein, spring means tending to balance the sash 45 at an intermediate point in its vertical movement, said elements having at each side coacting guide and engaging means comprising spaced substantially parallel vertical faces and spaced members for yieldingly engaging 50 said faces for frictionally resisting vertical sliding movement of the sash and permitting limited movement of the sash between the sides of the frame, said members being in engagement with said faces for the full height 55 of the sash during the full travel thereof whereby the sash will be held in any position of vertical adjustment when not balanced by the spring means.

15. In a window construction, a frame element, a sash element, vertically slidable therein, said elements having at each side coacting 60 guide and engaging means comprising spaced substantially parallel vertical faces and spaced members for yieldingly engaging said 65 faces for allowing vertical sliding movement

of the sash and permitting limited movement of the sash between the sides of the frame and allowing in and out movement of the sash, said members being in engagement with said faces for the full height of the sash during 70 the full travel thereof to provide a weather seal.
